(57) **CLAIM**

The ornamental design for a bed frame, as shown and described.

DESCRIPTION

FIG. 1 is a first perspective view of a bed frame showing the claimed design in accordance with the present disclosure; FIG. 2 is a second perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and

FIG. 8 is a bottom plan view thereof; and,

FIG. 9 is an enlarged view of an encircled portion 9 in FIG. 1.

The broken lines in the Figures are for the purpose of illustrating portions of the article that form no part of the claimed design.

The dash-broken lines encircling portions of the claimed design that are illustrated in enlargements form no part of the claimed design.
